(57) **CLAIM**

The new, original, and ornamental design for a video conference system, as shown and described.

DESCRIPTION

FIG. 1 is a top and left elevational view of a video conference system;

FIG. 2 is a right side elevational view thereof;

FIG. 3 is a front elevational view thereof;

FIG. 4 is a rear elevational view thereof;

FIG. 5 is a bottom plan view thereof;

FIG. 6 is a top plan view thereof;

FIG. 7 is a left side elevational view thereof; and,

FIG. 8 is a right side elevational view thereof.

The broken lines in the drawings depict environmental subject matter only and form no part of the claimed design.
